UNITED STATES PATENT OFFICE.

IRA W. NONNEMAN, OF WARREN, OHIO, ASSIGNOR TO THE BORDEN COMPANY, OF WARREN, OHIO, A CORPORATION OF OHIO.

DIESTOCK.

1,399,397.

Specification of Letters Patent.

Patented Dec. 6, 1921.

Application filed February 9, 1920. Serial No. 357,236.

To all whom it may concern:

Be it known that I, IRA W. NONNEMAN, a citizen of the United States, residing at Warren, in the county of Trumbull and State of Ohio, have invented a certain new and useful Improvement in Diestocks, of which the following is a full, clear, and exact description, reference being had to the accompanying drawings.

10 The general object of this invention is to provide a simple and effective threading tool capable of forming threads of different pitches on pipes, bolts and the like of various sizes.

15 My invention comprises the arrangement of a plurality of sets of chasers so carried in a single die stock that one set may be moved to operative position in which it may be adjusted for sizes while the other set of 20 chasers is held receded and in an inactive or idle position.

Another object of the invention is to provide practical means to cause movement of all of the chasers of one set simultaneously 25 from active to idle position and at the same time move the other set from idle to active position.

Still another object is to provide a satisfactory and conveniently operable locking 30 device for holding the chasers in any position given them.

My invention is hereinafter more fully explained in connection with the accompanying drawings. The essential characteristics 35 are summarized in the claims.

In the drawings Figure 1 is a side elevation of my die stock; Fig. 2 is an axial section through the same; Fig. 3 is a face or front view of the die stock; Fig. 4 is a 40 similar view with the front plates removed showing a means for actuating the sets of chasers alternately; Fig. 5 is a rear view of the die stock illustrating the adjustable guide; Fig. 6 is a detail of the cam plate for causing radial movement of the chasers; Fig. 7 is a diametric section through the same; Fig. 8 is a detail of one of the chasers removed; Fig. 9 is a detail of one of the rocking levers, for causing alternative 45 movement of the chasers; Fig. 10 is a detail of the cam plate for adjusting the guiding jaws.

50 The frame comprises substantially aligned inner sleeves 1 and 2 integral with a web 3 from which project flanges 4 and 5. Dia-

metrically opposite sockets 6 are employed for receiving the usual die stock handle 7.

The chasers of one set are designated 10 while chasers of the other set are designated 12. It will be noted that the chasers 60 are arranged in pairs and that one of each set in each pair of chasers is slidable with relation to the contiguous chasers. Each pair is slidably mounted in a radial slot, or opening, formed in the frame and extending through the sleeve 2 and flange 5.

The chasers of one of the sets are adapted to be moved by a cam plate. For example, the chasers 10 carry outwardly projecting pins or lugs 15 slidably engaging slots 70 16 in a revoluble plate-like ring 20, embracing the sleeve 2 and held in position by a nut 22 having wing projections 23 for convenience of rotating the nut by hand. This nut is shown as threaded to the sleeve 2 outside the plate 20. The periphery of the cam plate 20 is knurled whereby it may be conveniently rotated and, as will be seen from Fig. 6, such rotation causes radial movement of the chasers 10.

In order to obtain compactness and avoid confusion of cam slots, such as would be necessary in case another set of cam grooves were arranged for the chasers 12, I have provided a unique method of connecting the 85 chasers of the two sets so that as the chasers 10 are moved the chasers 12 are correspondingly moved in an opposite direction. This means comprises rocking levers 30 having

humps 31 and 32 rounded and abutting the 90 flanges 5 and 2, respectively, while at the ends of the levers are rounded knobs 33 and 34 which engage semi-cylindrical notches in the chasers as illustrated at 33^a in Fig. 8; thus as the chasers 10 moves outwardly it 95 moves the corresponding arm of the lever 30 outwardly, the lever itself pivoting and sliding between the two flanges and causing the knob 34 and chaser 12 to move inwardly radially a corresponding distance. The 100 notches in the chasers 10 and 12 are so arranged that one set of chasers may be in active position while the other is in idle position. Adjustment may be accomplished for different sizes by moving one set of 105 chasers a comparatively short distance radially by rotating the plate 20 without bringing the other set of chasers into a position in which they might interfere.

As a convenient means for guiding the die 110

stock on the pipe, I provide three or more radial jaws as illustrated at 40 sliding in slots formed in the sleeve 1, and flange 4, and having projections 41 engaging cam 5 slots 42 in a cam plate 45, embracing the sleeve 1 and adapted to be clamped against the end of flange 4 by a nut 50, threaded to the sleeve 1 and having suitable gripping wings 52. It will be seen that by rotating 10 this cam plate 45 the jaws may be moved radially to embrace the pipe or other article being threaded, and may be securely locked in such position by tightening the nut 50.

15 Having thus described my invention what I claim is:

1. The combination with a chaser carrying frame, a plurality of sets of radially movable chasers, a series of cams for actuating one set of chasers radially, and lever connections between each chaser of one set with a chaser of the other set, whereby inward movement of one set of chasers causes outward movement of the other set of 25 chasers.

2. The combination with a chaser carrying frame, a plurality of sets of radially movable chasers, means for actuating one of said chasers radially, and means whereby inward movement of one set of chasers causes outward movement of the other set of chasers.

3. The combination with a chaser carrying frame, a plurality of sets of radially movable chasers, means for actuating one set of chasers radially, and means connecting each chaser of one set with a chaser of the other set, whereby inward movement of one set of chasers causes outward movement of the other set of chasers.

40 4. The combination of a chaser carrying frame, a plurality of sets of radially movable chasers, means for simultaneously actuating one set of chasers radially, and a lever connection between each chaser of one set 45 with a chaser of the other set, whereby inward movement of one set of chasers causes outward movement of the other set of chasers.

5. In a die stock, the combination of a 50 chaser carrier, a cam plate rotatably mounted thereon, two sets of chasers radially movable in said carrier, one set having means engaging cam surfaces on said cam plate, rocking levers between each chaser of one set and a chaser of the other set and co-operating therewith, whereby movement of the chasers of one set, by the actuation of the cam plate, may move the chasers of the other set in an opposite direction.

60 6. In a die stock, the combination of a chaser carrying frame, two sets of chasers radially movable in said frame, means for moving all of the chasers in one set either inwardly or outwardly, a rocking lever between each chaser of one set and a chaser of

the other set and engaging therewith, each lever being adapted to cause the chasers engaged by it to be moved in opposite directions.

7. In a die stock, the combination of a 70 chaser carrying frame, two sets of chasers radially movable in said frame and arranged in pairs comprising a chaser of each set, means for moving all of the chasers in one set, either inwardly or outwardly, a rocking lever between each chaser of one set and a chaser of the other set and engaging therewith, each lever being adapted to cause the chasers engaged by it to be moved in opposite directions.

8. In a die stock the combination with a chaser carrying frame of two sets of chasers radially movable therein, two concentric shoulders on said frame, and a rocking lever pivotally engaging at one end a chaser of one set, and at the other end a chaser of the other set, and having rounded shoulders engaging said concentric shoulders.

9. The combination with a chaser carrying frame, of a plurality of sets of radially movable chasers, means for moving the chasers of one set radially simultaneously in the same direction, a lever connecting each chaser of one set with a chaser of the other set, the arms of the lever having pivotal engagement with each chaser engaged thereby, an outwardly projecting rounded shoulder on each lever forming its pivot, and a shoulder on said frame on which said pivot shoulder may rock and slide.

10. The combination with a chaser carrying frame having concentric shoulders, openings therethrough forming guide-ways for two sets of chasers arranged in pairs, each pair comprising a chaser of each set, a cam 105 plate rotatable concentrically of said shoulders and having eccentric cam slots, projections on each chaser of one set engaging said slots, means for locking said rotatable cam plate in any position given it, and a lever connection between the chasers moved directly by said plate and the chasers of the other set for moving said last mentioned chasers in the opposite direction.

11. The combination with a chaser carrying frame, of a plurality of sets of radially movable chasers, concentric shoulders having radial openings slidably receiving a chaser of each set, a revoluble plate having eccentric cams acting on the chasers of one 120 set, lever members each pivotally engaging a chaser of each set and having intermediate pivot shoulders extending both inwardly and outwardly, and concentric shoulders spaced apart and slidably engaged by said pivot 125 shoulders.

In testimony whereof, I hereunto affix my signature.

IRA W. NONNEMAN.
